Primary Examiner — Khawaja Anwar(74) *Attorney, Agent, or Firm* — Marshall, Gerstein & Borun LLP**CLAIM**

The ornamental design for a wheeled loading shovel vehicle, as shown and described.

DESCRIPTION

FIG. 1 is a front, right-side, and top view of a wheeled loading shovel vehicle showing one embodiment of the new design.

FIG. 2 is a front elevation view of the wheeled loading shovel vehicle.

FIG. 3 is a rear elevation view.

FIG. 4 is a right-side elevation view.

FIG. 5 is a left-side elevation view.

FIG. 6 is a top plan view; and,

FIG. 7 is a front, left-side, and top view.

The broken lines depict portions of the wheeled loading shovel vehicle that form no part of the claimed design.

1 Claim, 7 Drawing Sheets(56)
